US00D896225S

(12) **United States Design Patent** (10) **Patent No.:** **US D896,225 S**
(45) **Date of Patent:** ** *Sep. 15, 2020

(54) **CONNECTOR**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/665,742**

(22) Filed: **Oct. 5, 2018**

Related U.S. Application Data

(63) Continuation of application No. 29/642,630, filed on Mar. 30, 2018, now Pat. No. Des. 841,595, which is (Continued)

(57) **CLAIM**

The ornamental design for a connector, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a connector showing the claimed design.

1 Claim, 1 Drawing Sheet
(1 of 1 Drawing Sheet(s) Filed in Color)

Related U.S. Application Data

a continuation of application No. 29/558,758, filed on Mar. 21, 2016, now Pat. No. Des. 814,422, which is a continuation of application No. 29/529,183, filed on Jun. 4, 2015, now Pat. No. Des. 751,991, which is a continuation of application No. 29/449,244, filed on Mar. 14, 2013, now Pat. No. Des. 731,434, which is a continuation-in-part of application No. 29/432,034, filed on Sep. 12, 2012, now abandoned, and a continuation of application No. 29/426,587, filed on Jul. 6, 2012, now Pat. No. Des. 684,539.
